(57) CLAIM

The ornamental design for a transmission shifter, as shown and described.

DESCRIPTION

FIG. 1 is a front perspective view of a transmission shifter showing our new design;

FIG. 2 is a side view thereof;

FIG. 3 is a top view thereof;

FIG. 4 is a front thereof; and,

FIG. 5 is a rear view thereof.

It will be understood that the dashed lines presented in the drawings are for illustration only, and do not form a part of the claimed design.
